UNITED STATES PATENT OFFICE.

HARRY E. HULL, OF WILLIAMSBURG, IOWA.

CALCULATOR.

SPECIFICATION forming part of Letters Patent No. 601,470, dated March 29, 1898.

Application filed May 22, 1896. Serial No. 592,556. (No model.)

To all whom it may concern:

Be it known that I, HARRY E. HULL, a citizen of the United States, residing at Williamsburg, in the county of Iowa and State of Iowa, have invented certain new and useful Improvements in Calculators; and I do hereby declare the following to be a full, clear, and exact description of the invention, such as will enable others skilled in the art to which it appertains to make and use the same.

My invention relates to calculators or tables wherein the numbers representing ascertained results are arranged in columns and rows, the desired result in any case being the number at the intersection of some particular column and row.

The invention is designed to facilitate the finding of any desired number by mechanical means and with great accuracy, thus avoiding both the labor and liability to error incident to the tracing with the eye or by the aid of the finger of said columns and rows.

The nature of the invention will fully hereinafter appear, reference being had to the accompanying drawings, in which—

Figure 1, Sheet 1, is a plan view of a device embodying my invention. Fig. 2 is a rear view of the same with the back removed. Fig. 3 is a fragmentary front view of the tabular plate containing the ascertained results in regular columns and rows. Fig. 4, Sheet 2, is a rear view of the device with these tables removed. Fig. 5 is a central longitudinal section of the apparatus in a vertical plane. Fig. 6 is a fragmentary view showing a modification in the construction of the mechanism for shifting the parts which as moved from normal position expose some number of the table. Fig. 7, Sheet 3, is an illustrative view in perspective, showing one of the perforated slides, one of the imperforate slides, and one of the slotted tables with their connected key-levers. In this figure the number of columns does not correspond with those in the other figures, the view being simply for the purpose of illustrating more clearly the detail of construction of the various slides.

Similar letters of reference indicate corresponding parts.

Referring to the drawings, A designates a frame similar in the main to an ordinary picture-frame, in the front of the main opening

of which is mounted a perforated plate B. The holes b b in this plate are preferably made rectangular, so as to secure as large an opening as possible, the better to expose the numbers which are brought into view through them.

At one end of the frame is mounted as many series of push-buttons as the requirements of the calculator may demand, a triple series being shown, with an extra button to shift to normal position, as will be explained later. These buttons or keys E, D, F, G, and H are preferably mounted on bell-crank levers E', D', F', G', and H', pivoted to suitable lugs C' of a metallic plate C, secured to the frame by screws c c c c. The lower ends of the bell-cranks engage with the parts to be shifted, as will be hereinafter explained.

The keys are suitably marked with such numbers or characters as enter into the computation. The nature of the calculations may vary indefinitely, but for the sake of illustration a grain-table is used. The keys F and G are marked "60 lbs." and "75 lbs.," respectively, those being the number of pounds in bushels of certain kinds of grain. The series of keys D is marked with hundreds from "12" to "21," and the series E with tens from "0" to "90."

Referring now to Fig. 3, it will be seen that the tables of ascertained results for bushels of sixty and seventy-five pounds, respectively, are placed in regular rows and columns on thin slotted plates J and I, there being an opening between the columns of about the same width as the bar on which the columns of numbers are written. The numbers on the back plate may thus be brought to view by shifting it sidewise the space of a column. It will be understood that the tables of ascertained results marked on the slides I and J represent the sum of the first series of key-numbers plus the numbers of the second series of keys and divided by the characteristic number which each slide as a whole represents. For example, "16" in Fig. 3 stands for sixteen bushels, that being the number of seventy-five-pound bushels in twelve hundred pounds plus nothing. So "27" on the other slide is the number of sixty-pound bushels in sixteen hundred plus twenty pounds, as indicated by the buttons for the third column

and fifth row. It will be understood that in Fig. 3 the body of the plate I is behind and concealed by the plate J. The plates are each provided with a lateral extension I' and J', respectively, which connect with the lower ends of the levers F' and G', respectively. In front of these tables is mounted a series of thin vertical plates or slides K K of practically the same width as the column-spaces 5 of the plates I and J. These are separately attached to independent wires K' K', provided with suitable eyes at one end connecting with the bell-crank E' E'. In their normal position these slides are directly back of the openings 10 in the front plate B and thus cover the tables behind them. In front of these is a series of horizontal perforated end slides of thin material L, the openings l l of which are of practically the same dimensions as the 15 openings in the front plate and coincide therewith when shifted by their appropriate keys. These slides are coupled separately to the series of key-levers D' D' and are held in place by studs a a in suitable guide-slots l' l'. 20

25 The movable parts may be returned to normal position either by a supplemental shift-lever, as illustrated in the principal views, or by separate springs, as shown in Fig. 6. In the former case, which is preferable where a considerable number of keys are to be manipulated or where it is desired to allow the computation to stand after the fingers are withdrawn from the keys, the movable parts all engage with a shifter. A simple device for this purpose is illustrated in Figs. 4 and 5. M is a bail coupled to the shift-lever H' and having a longitudinal movement in suitable bearings m m m m. The movable parts I, J, K, and L are provided with suitable abutments i', j', 30 k', and l', respectively, to engage the end of the bail. When, therefore, any one of the parts is shifted, the bail moves with it. Conversely, the shifting of the bail back to normal position carries any and all the engaging 35 parts back to the same position.

40 Springs N may serve to restore the parts to normal position, as shown in Fig. 6. In this case when it is desired to lock the parts in the shifted position means are provided for 45 engaging the keys with some fixed part of the apparatus. A simple device is shown in Fig. 6, the key E being adapted to turn in the head of the key-lever and provided with a lateral lug at the lower end of its stem to engage the plate C when turned a short distance sidewise.

50 Studs n n, passing through slots i i, retain the tables I and J in proper place.

55 The parts are concealed from observation 60 and dust by a suitable backing A'.

The operation of the device will now be 65 readily understood. If, for example, it is desired to compute the number of bushels at sixty pounds per bushel in seventeen hundred and forty pounds, the operator pushes the key F, which brings the numbers of the

table I opposite the openings in the front plate B. All these openings are, however, closed by the slides K K and the perforated slides L L. On depressing the proper keys— 70 “1,700” of one series and “40” of the other series—a single opening is made, and this discloses the number “29,” which is the desired result.

75 It will be apparent that the device is adapted to a wide range of calculations by simply increasing the number of movable parts.

Having thus described my invention, I claim—

1. In a calculator, the combination with one or more tables, of a series of independent, narrow, longitudinally-movable, perforated slides, each adapted to cover or uncover a row of numbers on said table, a series of independent, imperforate plates arranged at right angles to said perforated slides, each of said plates being adapted to cover or uncover a column of numbers when moved, a series of stems to which said plates are respectively connected, said stems being parallel to the 80 perforated slides and movable in the same direction as said slides, and series of key-levers, one series being connected to the perforated slides and the other to the stems of the imperforate plates, substantially as described. 85 90 95

2. In a calculator, the combination with one or more tables, of a series of independent, narrow, longitudinally-movable, perforated slides, each adapted to cover or uncover a row of numbers on said table, a series of independent, imperforate plates arranged at right angles to said slides, each of said plates being adapted to cover or uncover a column of numbers when moved, a series of stems to which 100 said plates are respectively attached, said stems being parallel to and movable in the same direction as said perforated slides, a series of key-levers grouped at one side of the table, some of them connecting with the perforated slides and some with the stems of 105 the imperforate plates, a shifter adapted to engage all of said slides and imperforate plates and return any one of them to normal position, and a key-lever to actuate said shifter, 110 substantially as set forth. 115

3. In a calculator, the combination of a series or narrow, perforated, independently and longitudinally movable slides, each adapted to cover or uncover a single row of numbers, a series of independent, imperforate 120 plates arranged at right angles to said slides, each of said plates being adapted to cover or uncover a single column of numbers when moved, a series of stems to which said plates are separately connected, said stems being 125 parallel with and movable in the same direction as the perforated slides, one or more perforated tables with numbers arranged thereon in regular rows and columns, and adapted to move parallel with said slides, and a series of 130 key-levers at one side of the tables, some of which levers are connected to the perforated

slides, some to the stems of the imperforate plates, and some to the tables, substantially as described.

4. In a calculator, the combination of a series of narrow, perforated, independently and longitudinally movable slides, each adapted to cover or uncover a single row of numbers, a series of independent, imperforate plates arranged at right angles to said slides, each plate being adapted to cover or uncover a single column of numbers when moved, a series of stems to which said plates are separately attached, said stems being parallel with and movable in the same direction as the perforated slides, one or more tables of numbers

arranged in rows and columns, a series of key-levers at one side of said tables, and connecting independently with said perforated slides, the stems of the imperforate slides, and one or more of said tables, respectively, a catch 20 adapted to hold each key in a depressed position, and a shifter adapted to return any slide, imperforate plate, or table to normal position, substantially as described.

In testimony whereof I affix my signature 25 in presence of two witnesses.

HARRY E. HULL.
